United States Patent Office

Des. 228,613
Patented Oct. 16, 1973

228,613

CORKSCREW

Cipriano Ghidini, Brescia, Italy, assignor to Ray
Control Corp., New York, N.Y.

Filed Aug. 31, 1972, Ser. No. 285,167

Term of patent 14 years

Int. Cl. D7—06

U.S. Cl. D8—42

FIG. 1

FIG. 2

FIG. 3

FIG. 4

FIG. 1 is a top plan view of a corkscrew showing my new design;

FIG. 2 is a front elevational view thereof, the back view being identical thereto;

FIG. 3 is a left side elevational view thereof, the right side being identical thereto; and

FIG. 4 is a bottom plan view thereof.

I claim:

The ornamental design for a corkscrew, as shown and described.
